Primary Examiner — Marianne Pandozzi(74) *Attorney, Agent, or Firm* — Buche & Associates, P.C.;
John K. Buche(57) **CLAIM**

The ornamental design for a clipper organizer, as shown and described.

DESCRIPTION

FIG. 1 is a perspective view of a clipper organizer showing my new design;

FIG. 2 is a front elevational view of the clipper organizer;

FIG. 3 is a back elevational view of the clipper organizer;

FIG. 4 is a left side elevational view of the clipper organizer;

FIG. 5 is a right side elevational view of the clipper organizer;

FIG. 6 is a top view of the clipper organizer;

FIG. 7 is a bottom view of the clipper organizer; and,

FIG. 8 is an environmental perspective view of the clipper organizer.

The broken lines in the drawings are included for the purpose of illustration and form no part of the claimed design.
